CLAIM

The ornamental design for a side skirt for a car, as shown and described.

DESCRIPTION

FIG. 1 is a front perspective view of a side skirt for a car, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a state diagram of the side skirt for a car thereof;

FIG. 10 is a state diagram of the side skirt for a car thereof; and,

FIG. 11 is an enlarged detail view of area 11 in FIG. 2.

In the drawings, the broken lines depict environmental subject matter only and form no part of the claimed design. The dash-dot-dash broken lines in FIG. 2 represent boundaries of the enlarged portions and form no part of the claimed design.

The Truck in FIG. 10 shown in broken lines is for environmental subject matter only and forms no part of the claimed design.

The side skirt for a car is shown with a symbolic break in its length and the appearance of any portion of the side skirt for a car between the break lines form no part of the claimed design.
